August O. Tannenberg.

By Harry C. Schroeder
Attorney

UNITED STATES PATENT OFFICE.

AUGUST O. TANNENBERG, OF OAKLAND, CALIFORNIA.

PROCESS AND APPARATUS FOR PRODUCING FIBER FROM PALM LEAVES.

Application filed May 24, 1921. Serial No. 472,052.

To all whom it may concern:

Be it known that I, AUGUST O. TANNENBERG, a citizen of the United States, residing at Oakland, in the county of Alameda and State of California, have invented certain new and useful Improvements in Process and Apparatus for Producing Fiber from Palm Leaves, of which the following is a specification.

10 My invention is a new and useful process and apparatus for producing fiber of different thickness from palm leaves, for brooms, brushes or other articles.

15 Referring to the annexed drawing in which my invention is illustrated and which forms a part of this specification:

Figure 1 is a side view of my apparatus.

Figure 2 is a plan view of my apparatus showing a palm leaf being split to produce 20 fiber.

Figure 3 is a plan view of a palm leaf before it is split by my process and apparatus.

25 Figure 4 is a plan view of a palm leaf split by my process and apparatus into fiber.

Figure 5 is a side view of a broom made of the palm leaf fiber produced by my process and apparatus.

30 Figure 6 is a side view of a brush made of the palm leaf fiber produced by my process and apparatus.

In the drawing 1 indicates a base near one end of which is secured a standard 2 and on which are secured plates 3 and 4 of soft material such as leather. A lever 5 is fulcrumed at one end to the upper end of standard 2 by a pivot 6, on the other end of which lever is a handle 7. A set of knives 8, welded or otherwise secured parallel together are clamped by a clamp 9 to one side of the lever 5 at right angles thereto so that said knives rest vertically over the plate 3 when said lever is in a horizontal position with the lower cutting edges of the knives 45 engaging said plate. A set of parallel knives 10, spaced apart by blocks 11, are clamped together with said blocks, by a

clamp 12 to the same side of the lever 5 to which the knives 8 are clamped, at right angles to said lever so that said knives rest vertically over the plate 4 when the lever is in a horizontal position, with the lower edges of the knives engaging said plate. The clamp 9 is secured to the lever 5 by screws 13 and the clamp 12 is secured to 50 said lever by screws 14. The knives 8 are spaced close together for splitting thin fibers while the knives 10 are spaced further apart to split coarser fibers. The knives may be spaced at different distances apart for splitting fibers of different thickness by blocks 55 of different thickness.

In operation the lever 5 is held by the handle 7 in horizontal position with the lower edges of the knives 8 and 10 against 60 the plates 3 and 4 respectively, and the palm leaves 15 are drawn over the plates between said knives and split, producing the fibers as shown in Figure 2. The fibers may be used in brooms and brushes as shown in Figs. 65 5 and 6 and in many other useful articles.

The fibers are better split when green, but if they are hard and stiff they may be easily split if soaked in water for about one day. The fibers are best bent and put into shape 70 75 while damp, and when they are dry they are ready for use. The fibers will stand acid, turpentine, oil, lye, hot or cold water and may be boiled for an hour without losing their shape. If the fibers are bent out of 80 shape they may be straightened upon wetting them and hanging them up to dry, after which they are as good as ever.

Having described my invention, I claim:

In combination, a base, a lever fulcrumed 85 above the base, plates of soft material on the base and knives on the lever detachably secured to the same, the ends of the said knives being adapted to be brought into contact with the plates of soft material by means 90 of the lever.

In testimony whereof I affix my signature.

AUGUST O. TANNENBERG.
